WORKTABLE FOR SHOE SOLE STITCHING MACHINES

Stanley F. Graff, Minneapolis, Minn.

Application August 28, 1943, Serial No. 500,331

4 Claims. (Cl. 112—62)

1

My present invention relates to improvements in shoe stitching machines of the curved needle variety, and more particularly the invention provides an improved work table for such curved needle machines.

Particularly the improvement is directed to the provision of the work table with a detachable and replaceable needle plate, and with a sole guiding block or device which, without detachment or removal, may be given the finest and most minute kind of adjustments to vary the distance of the line of stitches from the edge of the sole.

In the accompanying drawings the improved features are shown as applied to the fixed arm of a shoe stitching machine such as is well known to the trade as the "Landis" machine.

Referring to the drawings wherein like characters indicate like parts throughout the several views:

Fig. 1 is a perspective showing some of the parts of the standard "Landis" curved needle machine and showing in detail the improved work table and attachments;

Fig. 2 is a section taken on the line 2—2 of Fig. 1;

Fig. 3 is a perspective showing the sole guiding block or element turned upside down;

Fig. 4 is a perspective showing a clamping block that forms an element of the means for securing the sole guide block to the work table;

Fig. 5 is a section taken on the line 5—5 of Fig. 4;

Fig. 6 is a perspective showing the work table with the detachable facing or needle plate removed therefrom;

Fig. 7 is a perspective showing the needle plate removed from the work table and the co-operating clamping screws removed from the needle plate;

Fig. 8 is an enlarged section taken on the line 8—8 of Fig. 1; and

Fig. 9 is a bottom plan view showing a portion of the sole of a shoe and indicating the line of stitches that secure the same to the shoe welt.

As above indicated the invention as illustrated is applied to the stitching machine of the "Landis" type. Of the well known parts of the machine, insofar as they are shown in the drawings, the numeral 10 indicates the fixed head, the numeral 11 the oscillatory needle guide, the numeral 12 the needle, the numeral 13 the awl and the numeral 14 the channel cutter that carries the presser foot 15. The needle and the awl are of the curved type carried by customary oscillatory devices, not shown, but which move the said awl

2

and needle through the same arc and through the opening in the work table.

In the standard machine the work table is formed on the extended end of a table supporting arm 16 which, in the drawings, is shown as rigidly secured to the fixed head 10 by means of a machine screw 17 and dowel pin 18 but which, of course, can be supported in any suitable way.

In the application of my invention, the fixed arm 16, at its extended end, carries the table. As a feature of invention the table is provided with a detachable needle plate or face plate. The table proper is preferably formed integral with the arm 16 and is a bifurcated or U-shaped structure, indicated at 19, and shown in detail in Fig. 6. This table 19 has the customary depending lip 20 that is engageable with the side of the shoe upper. The detachable needle plate, as best shown in Fig. 7, is a bifurcated structure 21 formed with an outer portion having a slot or needle passage 22. The needle passage 22 is formed in a vertically thickened portion of the needle plate that is seated in a depressed portion 23 of the table. The needle plate 21 is rigidly but detachably secured to the table by machine screws 24 or the like passed through perforations in the prongs of said needle plate and screwed into threaded seats 25 in the prongs of the table. The passage between the prongs of the table 19 is considerably wider than the passage between the prongs of the needle plate 21.

Fitted to slide in the space between the prongs of the table 19 and to bear against the overlying portions of the prongs of the needle plate 21 is a rectangular clamping block 26.

Seated to slide on the prongs of the needle plate 21 is a guide block 27 that is preferably of elongated rectangular form and is threaded to receive the threaded shank of a large clamping screw 28, see particularly Fig. 2. This clamping screw 28 at its lower end has a round head 29 that is seated to rotate in the annular recess of the clamping block 26. The threaded stem of the screw 28 works freely and with clearance 45 through a large central passage 26' of the clamping block 26.

Obviously with the structure described, when the clamping screw 28 is loosened the guide block 27 can be adjusted to just the desired distances 50 from the needle passage and from the line of movement of the needle; and when the said screw is tightened, the said block will be securely anchored to the needle plate or top element of the table. Of course, the clamping block 26 is freely movable with the guide block 27 and in the chan-

nel like seat formed therefor in the prongs of the table 19.

As an efficient and desirable way of tightening and loosening the clamping screw 28 the latter is shown as formed with an angular passage to receive the angular end of the wrench 30 shown in Fig. 8.

In Fig. 9 the shoe sole A is indicated as provided with two rows of stitches a located at different distances from the edge of the sole. Obviously, the guide block 27 can be accurately set to guide the shoe for the forming of stitches just the desired distances from the edge of the shoe sole. The shoe sole will, of course, bear against the front face of the guide block when the shoe is applied as shown in Fig. 8. In the said view, Fig. 8, the shoe sole is indicated by the character B, the shoe welt by the character C and the shoe upper by the character D.

In setting the guide block 27 it is only necessary to loosen the screw 28 enough to permit the sliding movement of the block and this, of course, can be done and the block relocked in a most accurate adjustment without at any time removing the guide block from the table.

In practice it has been found that it will often happen that the needle or the awl or both will be slightly bent and will engage the rim of the slot or passage in the table and deface the same so that replacement of the entire table has been necessary. With the face or needle plate made detachable, it is only necessary to replace the latter without the removal or renewing of the table. The shoulders formed between the offsets of the table and face plate serve to more accurately adjust these two elements before the screws 24 have been applied and tightened.

In actual practice the invention above described has been found thoroughly practical and desirable for the purposes had in view. Of course, the devices will be modified as to details of construction and arrangement of parts within the scope of the invention herein disclosed and claimed.

Whereas the invention is herein illustrated in connection with a "Landis" curved needle machine, it should be understood that the invention is equally adapted for use in connection with any curved needle shoe stitching machine.

What I claim is:

1. A work table for shoe sole stitching machines formed with a needle passage, said table having a shouldered longitudinal slot, a guide block seated on said table and having a portion working in the slot of said table, a clamping block working in said slot and having a clamping action on the shoulders thereof, and a clamping screw having a head rotatably mounted in said clamping block for sliding movement therewith and having threaded engagement with said guide block.
2. A work table for shoe sole stitching machines having a detachable face plate formed with a needle passage, said face plate having a slot at one side of said needle passage, said table having a wider slot under-lying the slot of said face plate, a guide block mounted on said face plate and provided with a portion extended into the slot of said face plate, a clamping block slidably mounted in the slot of said table and engaging the over-lying portion of said face plate, and a clamping screw having a head rotatably seated in said clamping block and having threaded engagement with said guide block.
3. The structure defined in claim 2 in which said detachable face plate and the body of said work table have over-lapping arm portions, and means detachably connecting the arm portions.
4. The structure defined in claim 2 in which said face plate and the body of said work table are formed with over-lapping U-shaped portions, the portion of said face plate in which the needle passage is formed being of increased thickness and fitting a depression formed by a reduced under-lying portion of said table.

STANLEY F. GRAFF.
